UNITED STATES PATENT OFFICE.

NEHEMIAH KIMBALL, OF BURRILLVILLE, RHODE ISLAND.

APPARATUS FOR LAYING RAILROAD-TRACKS.

SPECIFICATION forming part of Letters Patent No. 237,388, dated February 8, 1881.

Application filed September 1, 1879.

To all whom it may concern:

Be it known that I, NEHEMIAH KIMBALL, of Burrillville, in the county of Providence and State of Rhode Island, have invented a new and Improved Apparatus for Laying Railroad-Tracks; and I do hereby declare that the following specification, taken in connection with the accompanying drawings, forming a part of the same, is a full, clear, and exact description thereof.

The object of my invention is to perform the labor of moving and handling the material for the track—namely, the ties and rails—by mechanical contrivances, and to secure the rails to said ties after the latter have been properly bedded by the use of power-hammers for driving the spikes commonly employed to secure said rails in their places.

Said invention consists of a frame or structure adapted to be mounted on a platform-car, and provided with apparatus for lifting and conveying the rails and ties from said car to positions where they may be laid, and of hammers attached to such car for driving the spikes, all said apparatus being operated by steam or other appropriate power.

In the accompanying drawings, Figure 1 represents a perspective, and Fig. 2 a plan, of my apparatus; Fig. 3, a sectional side elevation on the line $x x$, Fig. 2; Figs. 4 and 5, details.

C denotes the car, and F a strong frame erected thereon, the forward part of which projects beyond the forward end of the car. Outside of the frame, on each side, is space on the car for loading the rails, and the ties may occupy the open space inside the frame.

B is a swing-bar mounted on the forward part of the frame, and provided at each end with suitable tackle, B', with which to lift the ties from the car and suspend them from the end of the swing-bar. To the ends of the bar are also attached the ropes R R', or their equivalents, which ropes extend toward the rear of the car, and are attached to pulleys P P' mounted on the shaft S. This shaft is placed across the rear end of the car, and is driven either by a small engine, also located on the car, or it may take the power upon the driving-pulley D from the locomotive. The shaft S turns in the pulleys P P', which are put in

motion by pressing them against cones V on the shaft S by means of the handles h h'; or in place of the cones a clutch-pin may be used. On each side of the frame is a carriage-rail, 55 A, from which a carriage, G, Fig. 4, is suspended on sheaves G'; and attached to this carriage, or forming a part of it, is a block and fall, D' a, leaving a clutch, K, for grasping a rail. The fall a extends from the block 60 to the forward part of the frame, passing over a pulley, E, near that end of the rail, and thence back to the pulley P'' on the shaft S. This last-named pulley receives the rope from each side of the frame and operates both carriages simultaneously. This is set in motion by friction on the cone V in the same manner as P and P'.

S' is a second shaft driven from the first, the receiving-pulley y on which is loose and 70 communicates its motion to the shaft by a friction-cone, V'. This shaft has two fast pulleys, y' y'', from which ropes a' extend to the carriage G for the purpose of drawing it rearward. A steam-hammer, H, is attached to the body 75 of the car on each side, at the forward end, so as to be directly over the rail on each side. The hammers are connected to the car by dovetailing cleats H' H'', as shown in Fig. 5, allowing of an adjustment forward or back, so 80 as to bring the hammers directly over a tie.

M is a steam-pipe to convey steam to the hammer.

The duty intended to be performed by the above-described apparatus is as follows: The 85 car loaded with rails and ties and propelled either by an engine placed thereon or a locomotive coupled behind it, and being located on a track, as shown in the drawings, where the work of laying new track is to begin, one end 90 of the swing-bar B is swung to the rear by setting the pulley P in motion. The end of the tackle-rope B' is made fast to a tie, which is then swung up from the car and the rope made fast. Pulley P' then swings the tie forward over its place on the road-bed, when it is dropped and planted. This is repeated until ties enough are laid to receive a new rail. Attendants then make fast each of the clutches K to a rail at about the middle part. Pulley 95 P'' first lifts the two rails by drawing up ropes a; but as the top of the clutch, or a check or

stop placed on the rope above the clutch, comes in contact with the block motion is imparted to the carriage and it is carried forward to the end of the carriage-rail A, which extends 5 beyond the end of the car a distance equal to or a little in excess of one-half the length of the road-rail. The pulley P'' is then set free from the friction-cone V, and the rails fall together on the track. It is preferable to use a 10 brake, such as shown at W, on this pulley in lowering the rails, in order that they may be let down gently. Such a brake may be arranged to be worked by the foot of the operator. The pulleys y' y'' afterward draw the 15 carriages back in position to take their next load. The car then moves forward far enough to bring the steam-hammers over the first tie under the newly-laid rails, or nearly so. The steam-hammers are adjusted by moving forward or back, if necessary, and drive the 20 spikes which secure the rails to the tie. At the same time a new tie is laid in advance. The car advances from tie to tie, driving the spikes and laying new ties. When the last 25 tie under the newly-laid pair of rails is reached a sufficient number of ties have been laid in advance to receive the next pair of rails. A spring-brake, X, producing a moderate friction on the shaft S', serves to arrest the tendency 30 of the carriages to move forward before the rails are lifted and cleared from the car.

Proper guides and supports for the various 35 ropes mentioned are of course contemplated where it is required to change direction or keep them in place.

The mechanism for handling the railroad-iron may be employed to advantage in loading the car from piles of rails lying alongside or near the road by employing a sufficient length 40 of rope to allow the clutch to be carried to the rails to be loaded.

By applying the friction through brake X to shaft S', heretofore mentioned, the carriages G are held stationary, and the rails are lifted 45 by means of the ropes and pulleys and deposited on the car, substantially as described for lifting the rails to be laid on the track.

This invention is also adapted to handling, lifting, and placing the timbers in building

elevated railroads after sufficient track has 50 been built on which to place the car.

What I claim as new, and desire to secure by Letters Patent, is—

1. In combination with the frame F, the carriage-rails A, secured along the top sides of 55 the frame, carriages G, running on said rails A, pulleys D' E, ropes a a', and operating-drums y' y'' and P'', all constructed, arranged, and adapted to operate substantially as and for the purposes described. 60

2. In combination with the frame F, the swing-bar B, pivoted to the top front portion of the frame, ropes R R', attached to each end of said swing-bar, and driving-pulleys P P', all substantially as and for the purposes de- 65 scribed.

3. In combination with the truck or car C, the steam-hammers H, secured to said car, substantially as and for the purposes described.

4. The combination and arrangement, in a 70 machine for laying railroad-tracks, of mechanism for carrying and depositing the cross-ties in proper position, consisting of a frame, F, mounted upon a car or truck, swing-bar B, ropes R R', and driving-pulleys P P', and 75 mechanism for carrying and depositing the rails in position upon the ties, consisting of carriage-rails A, carriages G, ropes a a', and driving-pulleys P'' y' y'', all substantially as and for the purposes described and shown. 80

5. The machine herein described for laying railroad-tracks, consisting of car C, frame F, secured thereto and projecting forward thereof, swing-bar B, with its ropes B' R R', carriage-rails A, carriages G, pulleys D' E, ropes a a', 85 clutches K K, driving-pulleys P P' P'' y y' y'', levers h h', and hammers H, all constructed, arranged, and adapted to operate substantially as set forth and shown, whereby a tie is lifted, and deposited in place on the road-bed, the 90 rails are raised, carried forward, and dropped in position on the cross-ties, and finally the rails are nailed in place, all in a regular continuous movement, by mechanical means.

NEHEMIAH KIMBALL.
